UNITED STATES PATENT OFFICE.

JOHN J. FOSS, OF CLEVELAND, OHIO.

DEVICE FOR LAYING OUT REGULAR POLYGONS.

SPECIFICATION forming part of Letters Patent No. 595,055, dated December 7, 1897.

Application filed March 19, 1897. Serial No. 628,259. (No model.)

To all whom it may concern:

Be it known that I, JOHN J. FOSS, a citizen of the United States, and a resident of Cleveland, county of Cuyahoga, and State of Ohio, have 5 invented a new and useful Improvement in Devices for Laying Out Regular Polygons, of which the following is a specification, the principle of the invention being herein explained and the best mode in which I have contemplated applying that principle, so as to distinguish it from other inventions.

The annexed drawings and the following description set forth in detail certain mechanism embodying the invention, such 15 closed means constituting but one of various mechanical forms in which the principle of the invention may be used.

In said annexed drawings, Figure I represents a top elevation of my device, showing 20 also the end of a bar or shaft. Fig. II represents a similar view looking at the bottom. Fig. III represents a vertical transverse cross-sectional view. Fig. IV represents a top elevation showing in addition an attachment to 25 the device; and Fig. V represents a view of a portion of my device, illustrating a modified use of same.

The tool consists of the two bars A and B, formed with the bifurcations a a' and b b' at 30 each end of each bar, the bifurcations a forming one angle, bifurcations a' forming another, b a third, and b' a fourth. The said angles are each equal to one of the interior angles of respective regular polygons which it is desired to lay out. The angles formed by a , a' , 35 b , and b' in the drawings are those of an equilateral triangle, a hexagon, an octagon, and a square, these polygons being of most common use. The said bifurcations are so formed 40 that a produced line bisecting the angle at one end of each bar will bisect the angle at the opposite end of the same bar. Each bar is formed with central longitudinal slots a^2 and b^2 of equal width. Two short bolts C, 45 provided with thumb-nuts C', are formed with a rectangular portion c, which snugly fits in and slides within the two slots a^2 and b^2 when the bars are laid one upon the other. It is thus seen that the two bars can be made to 50 slide one upon the other, the bisectors of their respective angles always remaining in the same plane passing longitudinally through

the middle of the bars. Their relative positions may be fixed by screwing down the thumb-nuts and clamping the two parts. 55

The heads c' of the bolts C are made square, the sides of said square being made parallel with the sides of the slots a^2 and b^2 . These square heads fit exactly a slot d of an attachment D, which is formed of a flat metal sheet 60 and has an extended portion d', whose inner longitudinal edge d' coincides with the produced middle line of the slot d. This edge, when the attachment is placed upon the bolt-heads, gives the bisecting line of the angle 65 to which it is applied.

It is desired to lay out a regular hexagon on the end of the shaft E, said hexagon having a diameter of one inch. The end of the shaft is inserted between the sides of the angle 70 formed by the bifurcations b' , which in this instance are opposite the bifurcations a' , which form an angle of one hundred and twenty degrees, the interior angle of a hexagon. The shaft is thus centered by resting 75 against both bifurcations, as is readily understood. The bar A is now slid up until the vertex of the angle of one hundred and twenty degrees is one inch from the center of the circle forming the end of the shaft. This center may have been previously determined by the use of the attachment D, two intersecting bisectors having been drawn upon the 80 shaft, their intersection being the center of the circle. The position of the vertex having 85 been determined, the two bars are firmly clamped together and a line is drawn upon the shaft, using the inside edge of one of the bifurcations a' as a straight edge. The shaft is then rotated on its axis until the line just 90 drawn coincides with the edge of the other bifurcation and a second line is drawn. The operation is repeated until all six sides have been drawn to complete the hexagon. Each of the other angles may be used in a similar 95 manner to form their respective polygons.

In Fig. V, I have shown how a polygon may be drawn upon a flat surface, as a sheet of paper upon a table, by the use of one bar. It is desired to inscribe a hexagon in the circle 100 F. An extended line f f is drawn through the center of the circle. The bar A is detached and laid upon the sheet with the vertex of the one-hundred-and-twenty-degree

angle coinciding with the intersection of the line *ff* with the circumference of the circle. The vertex of the angle at the opposite end is made to fall upon the extension of said line.

- 5 As before, a line is drawn using one bifurcation as a straight edge, the bar revolved until the edge of the other bifurcation coincides with the line just drawn, and a second line drawn. The operation is repeated until the 10 hexagon is completed.

Other modes of applying the principle of my invention may be employed instead of the one explained, change being made as regards the mechanism herein disclosed, provided the 15 means covered by any one of the following claims be employed.

I therefore particularly point out and distinctly claim as my invention—

1. In a device for laying out regular polygons, the combination with a bar provided 20 with two straight edges forming an interior angle of a regular polygon, of a second bar provided with two similar straight edges forming an interior angle of a regular polygon having a number of sides varying from 25

that of the first-named polygon, said two bars being longitudinally adjustable upon each other, the vertices of said angles always lying in the same plane perpendicular to the plane of one of said angles, substantially as set forth. 30

2. In a device for laying out regular polygons, the combination of a bar provided with two straight edges forming an interior angle of a regular polygon, of a second bar provided with similar straight edges forming an interior angle of the second polygon having a number of sides varying from that of the first-named polygon, each of said bars formed with a central longitudinal slot and longitudinally adjustable upon each other, and a bolt adapted 35 to slide within said slot and provided with means for clamping said two bars together, the vertices of said angles always lying in the same plane perpendicular to the plane of one of said angles, substantially as set forth. 40

Signed by me this 16th day of March, 1897. 45
JNO. J. FOSS.

Attest:

WILLIAM NOBBE,
A. E. MERKEL.
